(57) **CLAIM**

The ornamental design for a handle for a kitchen utensil or tool, as shown and described.

DESCRIPTION

FIG. 1 is a front view of a handle for a kitchen utensil or tool showing our new design;

FIG. 2 is a side view thereof, the opposite side view being a mirror image;

FIG. 3 is a cross-sectional view taken along the lines 3-3 from FIG. 1; and,

FIG. 4 is a front view thereof shown in an alternate condition and environment.

The broken line showing of a tool head is for the purpose of illustrating portions of the article and forms no part of the claimed design.
